UNITED STATES PATENT OFFICE

2,605,601

BEET TOPPER

Howard L. Toft, Caldwell, Idaho

Application March 11, 1949, Serial No. 81,002

2 Claims. (Cl. 56—121.4)

1

This invention relates to new and useful improvements in beet toppers and has for its object to provide a simply and inexpensively constructed device for splitting and cutting the tops of beets before the beets are lifted from the ground.

Another important object of this invention is to provide a beet crown cutter or topper that may be easily adjusted for slicing the beets at a desired point and which may be easily mounted as an attachment on any type of harvesting machine or the like.

Yet a further important object of this invention is to provide a device that will be yieldably mounted in such a manner so that it will automatically adjust itself to the uneven contour of the ground and to various heights of the growing beets and which during such adjustment will not change the desired angle or pitch of the blade.

These and ancillary objects and structural features of merit are attained by this invention, the preferred embodiment of which is set forth in the following description and illustrated in the accompanying drawings, wherein:

Figure 1 is a view in perspective of a beet topper constructed in accordance with the principles of the instant invention;

Figure 2 is a side elevational view thereof drawn to a smaller scale and showing the invention in adjusted position in dotted lines;

Figure 3 is a top plan view drawn to a smaller scale;

Figure 4 is an enlarged sectional view taken substantially on line 4—4 of Figure 2, looking in the direction of the arrows;

Figure 5 is a transverse sectional view taken substantially on line 5—5 of Figure 4, looking in the direction of the arrows; and

Figure 6 is a view in perspective of the blade.

Referring now more particularly to the drawings, this invention, designated generally by the reference character 10, consists of a blade 12, having a bevelled or inclined cutting edge 14. The blade 12 is adapted to travel along a row of plants parallel to the ground, as seen in Figure 2, with the cutting edge 14 carried in cutting contact with a row of longitudinally aligned beets 16. The blade is formed with an integral upright lateral attaching flange 18, which is provided with a pair of elongated parallel slots 20 and 22. A substantially L-shaped bracket 24 is provided on top of a shield 28, presently described, and the flange 18 is adjustably affixed to said bracket 24 by conventional fastening members 26 slidably disposed in the slots 20 and 22, whereby the blade may be raised and lowered and positioned

at the desired point with respect to the ground. The bracket 24 is formed integral with the shield 28, which includes an upwardly extending concavo-convex portion 30 having parallel reinforcing ribs 32 disposed longitudinally on the upper face thereof. A rearwardly and substantially horizontally disposed trailing edge 34 is formed integrally on the shield and is positioned slightly in advance and above the blade 12. The shield 28 is provided to prevent various obstructions from contacting the blade and functions to clear debris and other matter in the path of the blade. However, it is to be noted that the shield and especially the trailing edge 34 thereof are spaced upwardly from the blade 12 so as to clear the tops of the beets and thus not interfere with the cutting of the beet tops by the blade. A vertically disposed bar 36 is formed integrally with the shield and extends upwardly from the trailing edge 34 thereof. The bar supports the blade in a yielding manner so that the blade may freely move upwardly and automatically adjust itself to the heights of different beets above the ground surface and to the uneven contour of the ground.

25 The bar 36 is slidably disposed between a pair of plates 38 and 40. The plates are held together in a spaced manner by fastening means 42. The fastening means include bolts 44 which are inserted transversely through the plates and provided with nuts 46 spaced on the plates by washers 48. Upper and lower pairs of rollers 56, 58 are rotatably supported on bushings or sleeves 52 concentrically disposed on the shank of the bolts between the opposing inner faces of the plates and the rollers 56, 58 are spaced from the plates by spacing washers 54.

Thus, as seen in Figures 4 and 5, the bar 36 is slidably disposed between an upper pair of spaced horizontally aligned rollers 56 and a lower pair of horizontally aligned and spaced rollers 58, the latter pair being disposed in vertical alignment with the upper pair.

Means is provided for resiliently retaining the blade in its lowered position and for yieldably holding the blade to permit the same to slice the beets at the desired point. The means preferably includes a pair of springs 60 and 62 which are disposed on opposite sides of the bar and secured at the upper edge thereof by a transversely disposed bolt and nut assembly 64. The lower ends of the springs are secured in perforated ears 66 which are formed integrally on the outer faces of the plates 38 and 40 and disposed at the lower end thereof. An L-shaped bracket 68 is formed integrally with the plate 40 and the vertical leg

70 thereof is adapted for detachable and adjustable attachment to a harvesting machine or the like machine.

The vertical leg 70 of the L-shaped bracket is disposed slidably between aligned openings 72 and 74 formed in the opposing legs 76 and 78 of a U-shaped bracket 80. The legs 76 and 78 terminate in lateral clamping ends 82 and 84 which are adapted for attachment to extending portions 86 of the harvesting machine or the like. A set screw 88 is disposed through the bight or web 90 of the bracket 80 and is adapted to bear against the vertical leg 70 of the bracket 68 and frictionally retain said leg in the desired position.

Thus, it can be seen that the beet topping attachment can be easily secured to any type of machine or implement carrier and the attaching bracket 68 can be adjustably attached to the machine so as to position the blade 12 at the desired distance from the ground. It is to be noted that, as the device is drawn over the ground, the blade 12 will easily remove the beet tops, the blade following the runner blade 34 and slicing the beets at the desired point. Of course, it can be seen that the bar 36 will move upwardly in the track-way defined by the pair of complementary rollers to automatically adjust itself to the various heights of the beets and the uneven contour of the ground, the movement of the bar 36 being responsive to the engagement of the beet tops by the forward blade or runner blade 34. Of course, the movement of the bar 36, in its vertically reciprocal path, will not alter the angle of the blade 12 and, therefore, the beet tops will be cut in the same manner as the blade is moved over the longitudinal row of beets.

It is to be apparent that said device can be easily used for other operations, including various

other types of cutting operations, or another implement could be substituted for the blade 12, such as a rake or the like or other agricultural operation.

Having described the invention, what is claimed as new is:

1. A beet topper adapted to be carried forwardly over the ground by a vehicle comprising an upwardly and forwardly extending shield for riding over the beet tops having a concavo-convex portion with the concave side facing the ground, said shield having a trailing horizontal edge portion, a bar upstanding from said trailing edge portion and formed integrally therewith, a beet topper blade having a cutting edge, means mounting said blade on said shield below the same with the cutting edge forwardly and parallel with said trailing edge comprising a bracket on top of said shield extending rearwardly therefrom, and an end flange on said blade secured to said bracket, and supporting means for said bar attachable to said vehicle.

2. A beet topper according to claim 1, wherein bolts on said bracket and slots in said flange provide for tiltably adjusting said blade to raise or lower the cutting edge thereof.

HOWARD L. TOFT.
